APPARATUS FOR COOKING AND DRYING

Original Filed April 13, 1929

FIG. 1.

FIG. 2.

FIG. 3.

Howell S. Vincent Inventor

By Ogle R. Singleton.

Attorney

UNITED STATES PATENT OFFICE

HOWELL SMITH VINCENT, OF BROOKLINE, MASSACHUSETTS

APPARATUS FOR COOKING AND DRYING

Original application filed April 13, 1929, Serial No. 354,967. Divided and this application filed February 13, 1930. Serial No. 429,441.

My invention consists in a new and useful improvement in apparatus for cooking and drying. This application is a divisional application from my application Serial Number 5 354,967, filed in the United States Patent Office on April 13, 1929.

The particularly novel and useful features of my invention described and claimed herein are the combination of a cooking chamber 10 and a drying chamber, and means for the heating and circulation of air to serve the double use of the evacuation of odorous fumes from the cooking chamber and the passage of heated air through the drying chamber 15 ber.

In the drawings:

Fig. 1 is a plan view of my device.

Fig. 2 is a vertical section on the line 2—2 of Fig. 1.

20 Fig. 3 is a vertical section on the line 3—3 of Fig. 1.

I provide a vertically movable insulated chamber 1 having the insulated top 2 with an inner lining 3, the outer insulated end wall 25 4 with inner lining 5, the insulated bottom 6 with inner lining 7, the inner uninsulated end wall 8, the rear insulated side wall (not shown) with inner lining 9. The side of the chamber 1 which is toward the front is open 30 for access to the chamber 1, but I may provide a suitable movable closure therefor, if desired.

The chamber 1, as above described, when in normal position, is received in a casing C 35 upon which the top 2 fits to form a closed chamber.

I provide three elevating means 10 comprising pneumatically operated tubes, upon which the chamber 1 is mounted, and by 40 which it may be moved out of the casing C.

Upon the lining 7 of the bottom 6 of the chamber 1, I provide any desired number of electric hot plates 11, and depending from the top 2 I provide the hot plate 12.

45 Suitably mounted on the casing C at a point adjacent the bottom 6 of the chamber 1, there is the pipe 13 square in cross section which passes upwardly in juxtaposition with the wall 8 which is disposed at that point to encase the pipe 13 on two of its sides. This

pipe 13 is provided near its upper end on its side away from the chamber 1 with a port 14. Slidably received in the pipe 13 is the pipe 15 having the elongated slot 16 so disposed as to be in constant register with the port 14 in the pipe 13. The pipe 15 is supported by its elbow 17 attached to the inner side of the top 2 and disposed adjacent the front edge thereof, and provided with the longitudinal slot 18.

55 Adjacent the chamber 1, there is mounted in the casing C the chamber 19 formed by the walls 20, 21, 22 and 23, the bottom 24 and the hinged top 25. It is to be noted that the wall 21 merges with the pipe 13 so that the port 14 of the pipe 13 opens into the chamber 19. Passing through the bottom 24 is the vent pipe 26 connected with the evacuator fan 27, driven by the motor M, and having the discharge pipe 28. Suitably disposed in the bottom 24 is the discharge opening 29 controlled by the slide valve 30, slidably mounted on the underside of the bottom 24 and having the operating handle 31 conveniently positioned on the casing C. It is to be noted that 60 the bottom 24 is downwardly inclined toward the opening 29, to facilitate discharge of material therethrough.

65 I will now describe the use and operation of my device. It is to be understood that suitable manually-operated control means for the elevating means 10 is suitably positioned on the casing C. By the operation of this means the operator may cause the chamber 1 to rise 70 out of the casing C and thus render easily 75 accessible for use the hot plates 11 so that the chamber 1 may serve as a grill. It is to be understood that any suitable form of manually-operated control means for the plates 11 and 12 are provided. It is to be understood 80 that any suitable manually-operated control means for the motor M is suitably situated. By the manipulation of this means the operator may cause the fan 27 to induce a current of air through the slot 18 in the elbow 17, 85 and the pipe 15 and through the chamber 19 and pipes 26 and 28, thus serving to remove any odorous fumes caused by the operation of the hot plates 11. When it is desired to utilize the chamber 1 as an oven, it may be raised 90 95 100

into the position heretofore described and after the articles to be cooked in the oven are placed in the chamber 1, it is returned to normal position thus being enclosed by the casting C and heat supplied by the plates 11 and 12.

By raising the hinged lid 25 the operator has access to chamber 19 and may deposit undesirable refuse therein. When the lid 10 25 is closed, the refuse is confined in a substantially air-tight chamber through which heated air may be circulated as above described, thereby dessicating the refuse which may be discharged by gravity from the chamber 19 by opening the discharge valve 30, and disposed of in any suitable way.

Having described my invention, what I claim is:

1. The combination of a chamber; a pipe in said chamber; a receptacle vertically movable into and out of said chamber; a pipe in said receptacle having a slot therein; an elbow attached to said receptacle pipe, slideable in the chamber pipe, and provided with a slot; a second chamber, adjacent the first mentioned chamber, provided with a port in communication with the slot in the elbow; and means adapted to draw air from the receptacle through its pipe and elbow and the 25 said second chamber.

2. The combination of a chamber; a pipe in said chamber; a receptacle movable into and out of said chamber; a second pipe mounted in said receptacle and having a portion slidably received in said first mentioned pipe; a second chamber adjacent said first mentioned chamber and provided with a port in communication with the pipe in the first mentioned chamber; and means adapted to draw air from the receptacle through both pipes and said second mentioned chamber.

3. In a cooking and drying apparatus, the combination of a base; a receptacle provided with cooking means and means adapted to move said receptacle into various positions of adjustment relative to said base; a second receptacle in said base; and means adapted to evacuate air from said first receptacle and through said second receptacle, when the first receptacle is in any of its adjusted positions.

In testimony whereof I affix my signature.
HOWELL SMITH VINCENT.
